UNITED STATES PATENT OFFICE.

ELIAS N. MILLER, OF DENVER, COLORADO.

TIE.

Application filed May 2, 1925. Serial No. 27,510.

To all whom it may concern:

Be it known that I, ELIAS N. MILLER, a citizen of the United States, residing at Denver, in the county of Denver and State 5 of Colorado, have invented certain new and useful Improvements in Ties, of which the following is a specification, reference being had to the accompanying drawings.

This invention relates to certain improvements in ties and has relation more particularly to devices of this kind especially adapted for use in connection with concrete molds and the like, and it is an object of 10 the invention to provide a tie of this kind which may be readily applied into working 15 position and which is preferably formed from a single strand of wire of requisite gauge.

Another object of the invention is to provide a device of this kind which may be employed to advantage in tying either metal or wood forms and which can be used in connection with any kind of uprights, either 20 metal or wood.

25 The invention consists in the details of construction and in the combination and arrangement of the several parts of my improved tie whereby certain important advantages are attained and the device rendered simpler, less expensive and otherwise 30 more convenient and advantageous for use, as will be hereinafter more fully set forth.

The novel features of my invention will hereinafter be definitely claimed.

35 In order that my invention may be the better understood, I will now proceed to describe the same with reference to the accompanying drawings, wherein:—

40 Figure 1 is a fragmentary view in top plan and of somewhat a diagrammatic character illustrating ties constructed in accordance with an embodiment of my invention in applied position;

45 Figure 2 is an enlarged fragmentary vertical sectional view taken through a form showing a tie constructed in accordance with an embodiment of my invention in applied position;

50 Figure 3 is an enlarged view in plan of a tie as herein disclosed.

55 As disclosed in the accompanying drawings, my improved tie is formed of a single length or strand of wire of requisite gauge and comprises a central or intermediate 60 length 1 having its opposite end portions 65 respectively returned to provide the lengths 2

and 3 each of which having is free end terminating inwardly of the adjacent end of the intermediate length 1. The portions of the lengths 1, 2 and 3 between the free extremities of the lengths 1 and 2 are coiled or wrapped one around the others whereby the central major portion of the tie possesses considerable strength and is substantially 65 free from bending.

The connected end portions of the lengths 1 and 2 and 1 and 3 outwardly of the free ends of the lengths 2 and 3 are separated to provide the loops 4 which are adapted to be engaged around the external uprights 5 70 comprised in a form for concrete or the like with the tie extending through the filler between the front and back walls 6 of the form. The free extremity of the length 2 is coiled, as at 7, around the lengths 1 and 2 at the inner end of the loop 4 adjacent to said coil 7 while the free end portion of the length 3 is coiled, as at 8, around the lengths 1 and 2 at the inner portion of the loop 4 immediately adjacent to said coil 8. 75

A tie as herein disclosed can be readily used in tying either metal or wood forms and can be used in connection with any kind of uprights, either metal or wood, as the loops 4 can be made any desired size and the various lengths comprised in the tie may be varied in accordance with the necessity of practice as is also true of the gauge 80 of the wire.

While the invention as herein described 90 and illustrated shows the use of a single strand it is to be understood that two or more strands may be employed to provide what may be termed a duplex tie when it is required to increase the strength thereof. 95

From the foregoing description it is thought to be obvious that a tie constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish 100 to be understood as limiting myself to the precise arrangement and formation of the several parts herein shown in carrying out my invention in practice except as herein-after claimed.

110 I claim:—

1. As a new article of manufacture, a tie

for plastic forms formed of a single strand of wire and of a length to bridge the space between and extend outwardly beyond opposed walls of such form, said tie comprising an intermediate length, the extremities of said intermediate length being continued by returned lengths, each of the returned lengths terminating inwardly of the opposite end of the intermediate length, each end portion of the intermediate length and the connected portion of the adjacent returned length being separated to provide a loop, the portions of the three lengths between the loops being wrapped one around the other two.

2. As a new article of manufacture, a tie for plastic forms formed of a single strand of wire and of a length to bridge the space between and extend outwardly beyond op-

posed walls of such form, said tie comprising an intermediate length, the extremities of said intermediate length being continued by returned lengths, each of the returned lengths terminating inwardly of the opposite end of the intermediate length, each end portion of the intermediate length and the connected portion of the adjacent returned length being separated to provide a loop, the portions of the three lengths between the loops being wrapped one around the other two, the extremities of each of the returned lengths being coiled around the other lengths at the inner end of a loop.

In testimony whereof I hereunto affix my signature.

ELIAS N. MILLER.
